UNITED STATES PATENT OFFICE

JOHN H. VERNET, OF OAK PARK, ILLINOIS

HEATING DEVICE

Application filed August 18, 1930. Serial No. 476,068.

This invention relates to a heating plug and particularly to a heating plug adapted for use in connection with hot water bottles. It has for one object to provide a plug which is thermostatically controlled so as to provide a heating source of constant temperature. Another object is to provide a plug of the type suggested in which the heating element projects only a short distance into the hot water bottle so that the fabric of the bottle or bag will not be brought in contact with the heating element.

Another object is to provide in a plug of the type suggested a heating element which, while projecting into the receptacle to which the plug is applied, is held out of contact with the contents of the receptacle.

Other objects will appear from time to time in the specification and claims.

20 The invention is illustrated more or less diagrammatically in the accompanying drawing, in which;

Figure 1 is a side elevation;

Fig. 2 is a partial longitudinal view taken 25 at line 2—2 of Fig. 1; and

Fig. 3 is a transverse cross section taken at line 3—3 of Fig. 2.

Like parts are designated by like characters throughout.

30 A is a plug body. It may be flattened as at A¹. It is provided with a threaded portion A² from which may extend a shielding or covering element A³ of generally cylindrical shape. The member A³ is provided with one or more perforations or openings A⁴ in its sides and may have an open end A⁶. Adjacent the open end A⁶ is an inwardly extending flange A⁷. A⁸ is a cavity within the body of the plug A. A⁹ is an air passage leading 35 from the lower or inner end of the plug A and communicating with the cavity A⁸. A¹⁰ is a closure for the cavity A⁸. This closure is 40 provided with a perforation A¹¹.

Fixed in the plug A is a conducting or contact member B. It is provided with a downwardly extending portion B¹ which may or may not be made integrally with it. B² is a second conducting or contact member generally similar to the member B. It is provided with an adjustably positioned contact

member B³, which is preferably threaded in it and which is adapted to contact with the thermostatic element B⁴ positioned within the cavity A⁸ upon a plug B⁵, upon which it is removably held by a screw B⁶. A downward extension B⁷ runs from the plug B⁵ into the cavity provided within the extension A³ of the plug body A. B⁸ is a heating element, which in the form here shown is a coiled wire or filament and extends from the member B¹ 55 to the member B⁷. It is of such material that it becomes highly heated when an electric current is passed through it. B⁹ is a shielding member which may be of metal. It lies within the extension A³, encloses the downward or inner ends of the members B¹, B⁷ and the heating element B⁸ and holds these elements out of contact with the contents of a receptacle to which the plug may be applied.

C is a housing for the connecting members. C¹ is a second part of the housing and it may be removably attached to the member C by means of a screw C². The member C¹ is provided with two cavities C³, C⁴, in which spring contact members C⁴ are positioned. 65 These members are adapted to contact with the members B—B² as shown in Fig. 2, and are connected in any suitable manner with conductors C⁵, C⁶. These conductors may be provided with insulating coatings C⁶, C⁶ 70 and are preferably covered together by a sheathing C⁷.

Although I have shown in my drawing an operative device, it will be obvious that many changes in form, shape and arrangement of parts may be made without departing from the spirit of my invention.

Particularly, the thermostatic feature might be omitted; the shape and design of the plug might be altered; and the shape and design of the contact carrying portion of the plug might be altered.

The use and operation of this invention are as follows:

The thermostatic element B⁴ may be made 85 of any design which will cause it to move or change shape, in response to variations of temperature, so that it is effective to break the circuit preferably by moving out of contact with the point of the member B³ at a 90 100

given temperature and thus when the temperature rises about the maximum desirable temperature, the circuit is broken automatically by this movement of the thermostatic element, and the circuit is not again made until the parts have cooled down to the desired temperature, then the circuit is again made and heating again continues. The adjustment of the parts is preferably effected by 10 moving the screw B^3 in and out with respect to the thermostat B^4 . When the device is to be used, it is connected with the source of current, the plug is screwed into an opening in a receptacle, for example, with a flexible 15 hot water bottle, which is more or less filled with liquid. The current then being applied passes through the various contacting elements shown and through the heating coil B^8 , thus heating it. The cap B^9 becomes 20 heated, and, since it is in contact with the fluid, that is heated, but the fluid forms no part of the electrical circuit and current is not passed through it.

As above described, the thermostat is effective to provide a constant temperature. The 25 passage A^9 and the perforation A^{11} are provided to permit expansion and contraction of air from the interior of the cap B^9 .

The device might be further changed by 30 having one or both of the members B^1 , B^7 in contact with the cap B^9 , or one or both of the ends of the coil B^8 might be in contact with the cap B^9 . Thus heat would be conducted from the coil B^8 to the cap B^9 directly by 35 conduction and not by convection.

I claim:—

1. In a heating plug adapted for use in connection with a liquid containing receptacle as a means for heating the liquid, a plug 40 housing shaped to be positioned within an opening in the receptacle, the plug including electrical conductors, said conductors extending inwardly beyond the end of the plug housing, a heating element in circuit with said conductors, a cap surrounding said heating element and holding it out of contact with the liquid within the receptacle, the plug housing shaped to surround the cap and provided with perforations whereby liquid within 45 the container reaches the cap.

2. In a heating plug adapted for use in connection with a liquid containing receptacle as a means for heating the liquid, a plug housing shaped to be positioned with an opening in 50 the receptacle, the plug including a pair of electrical conductors, said conductors extending inwardly beyond the end of the plug housing, a heating element in circuit with said conductors, a cap surrounding said heating 55 element and holding it out of contact with the liquid within the receptacle, the plug housing shaped to surround the cap and provided with perforations whereby liquid within the container reaches the cap.

60 3. In a heating plug adapted for use in

connection with a liquid containing receptacle as a means for heating the liquid, a plug 70 housing shaped to be positioned within an opening in the receptacle, the plug including a pair of electrical conductors, said conductors extending inwardly beyond the end of the plug housing, a heating element in circuit with said conductors, a metallic cap surrounding said heating element and holding it out of contact with the liquid within the receptacle, the plug housing shaped to surround the cap and provided with perforations whereby liquid within the container reaches the cap. 75

4. In a heating plug adapted for use in connection with a liquid containing receptacle as a means for heating the liquid, a plug 80 housing shaped to be positioned within an opening in the receptacle, the plug including a pair of electrical conductors and a thermostatic element in circuit in one, a heating element in circuit with said conductors, a cap surrounding said heating element and holding it out of contact with the liquid within the receptacle, the plug housing shaped to surround the cap and provided with perforations whereby liquid within the container reaches the cap. 85

5. In a heating plug adapted for use in connection with a liquid containing receptacle as a means for heating the liquid, a plug 90 housing shaped to be positioned within an opening in the receptacle, the plug including a pair of electrical conductors and a thermostatic element in circuit in one, said conductors extending inwardly beyond the end of the plug housing, a heating element in circuit with said conductors, a metallic cap surrounding said heating element and holding it out of contact with the liquid within the receptacle, the plug housing shaped to surround the cap and provided with perforations whereby liquid within the container reaches the cap. 95

6. In a heating plug adapted for use in connection with a liquid containing receptacle as a means for heating the liquid, a plug 100 housing shaped to be positioned within an opening in the receptacle, the plug including electrical conductors, a heating element in circuit with said conductors, a cap surrounding said heating element holding it out of contact with the liquid within the receptacle, the cap projecting inwardly slightly from the end of the housing whereby the receptacle is prevented from coming into contact with the walls of the cap. 110

7. In a heating plug adapted for use in connection with a liquid containing receptacle as a means for heating the liquid, a plug 115 housing shaped to be positioned within an opening in the receptacle, the plug including a pair of electrical conductors, a cap surrounding said heating element and holding it out of contact with the liquid within the receptacle, the cap projecting inwardly slightly from the end of the housing whereby 120

125

the receptacle is prevented from coming into contact with the walls of the cap.

8. In a heating plug adapted for use in connection with a liquid containing receptacle 5 as a means for heating the liquid, a plug housing shaped to be positioned within an opening in the receptacle, the plug including a pair of electrical conductors, said conductors extending inwardly beyond the end of the 10 plug housing, a heating element in circuit with said conductors, a metallic cap surrounding said heating element and holding it out of contact with the liquid within the receptacle, the cap projecting inwardly slightly 15 from the end of the housing whereby the receptacle is prevented from coming into contact with the walls of the cap.

Signed at Chicago, county of Cook and State of Illinois, this 13th day of August, 20 1930.

JOHN H. VERNET.
